DOUBLE ROCKER ARM ASSEMBLY

Paul F. Bergmann, North Muskegon, Mich., assignor to Johnson Products, Inc., Muskegon, Mich., a corporation of Michigan

Filed Nov. 2, 1959, Ser. No. 850,187

11 Claims. (Cl. 123—90)

This invention pertains to a rocker arm assembly and more particularly to a double rocker arm assembly.

Previously rocker arms have been positioned with respect to the push rods and valve stems of an engine by securing them to a rocker arm shaft, or by securing them individually on a fastener. To secure the rocker arm to a rocker arm shaft it has been necessary to provide the rocker arm with some type of aperture so that the rocker arm can be positioned on the rocker arm shaft and rotate thereabout. Such apertures in the rocker arm tend to weaken the rocker arm because it is constructed of the minimum amount of material necessary for economy purposes, and the amount of material between the aperture and the edge of the rocker arm is not always sufficient for proper strength. Therefore, frequently cracks form between the aperture and the edge of the material and serious trouble results. The same problem is present where the rocker arm is secured in position by means of a single fastener. This arrangement of the rocker arm necessitates an aperture through the central portion thereof and the same type of cracking and breakage between the edge of the rocker arm and the aperture will result. It is therefore an object of this invention to disclose a rocker arm that can be secured in the proper position without the necessity of forming an aperture therein.

It is another object of this invention to disclose a rocker arm that is secured in position without the use of a rocker arm shaft or a fastener extending therethrough.

Still another object of this invention is to disclose a double rocker arm assembly in which the rocker arms are disposed in pairs.

A further object of this invention is to disclose a rocker arm that is suspended and secured in position by means of a spring clip.

Another object of this invention is to disclose a rocker arm that is easily lubricated.

Still another object of this invention is to disclose a rocker arm assembly that will reduce harmonic vibrations.

Another object of this invention is to disclose a rocker arm that can be stamped or pressed from steel.

These and other objects and advantages of the practice of this invention will be more apparent in the illustration and description of the working embodiment of the invention, as hereinafter set forth.

In the drawings:

Fig. 1 shows a side elevational view of the double rocker arm assembly.

Fig. 2 shows a top plan view of Fig. 1.

Fig. 3 shows a cross sectional view taken along the plane III—III of Fig. 1.

Fig. 4 is a perspective view of a rocker.

The rocker arm assembly of this invention is shown as it would be mounted in an engine. The push rods and valve stems are shown to illustrate how the rocker arm assembly is associated therewith.

Referring in greater detail to the drawings, Fig. 1

2

shows a portion of the engine block 11. The engine block 11 is seen to have a surface 26 which forms a foundation for the base support 12. The base support 12 is a rectangularly shaped member and has an aperture 5 therein adapted to receive a bolt for securing the rocker arm assembly to the engine block.

The bottom of the base support member is machined to correspond with the surface 26 of the engine block 11. The top of the base support member 12 has a U-shaped groove machined therein across the width thereof to provide a saddle for a rocker fulcrum now to be described.

The rocker fulcrum 13 is of a U-shaped design as best shown in Fig. 1. The fulcrum has an outside bearing surface 41, dimensioned so as to form a bearing fit with the U-shaped groove in the base support member 12, and in the assembled position fits snugly in the saddle formed by the groove in the base support member 12. The rocker fulcrum 13 is of a length so that it extends beyond both sides of the base support 12 to form a fulcrum for the rocker arms. This feature will be explained more fully hereinafter. The fulcrum 13 has an aperture disposed centrally therein to correspond with the aperture in the base support 12.

25 A clamping block 14 is designed to fit within the U-shaped rocker fulcrum 13 and clamp the U-shaped rocker fulcrum member 13 to the base support 12. The bottom of the clamp block 14 is machined to correspond in design and dimension to the inside of the U-shaped rocker fulcrum 13 as best shown in Fig. 1. The clamping block 14 is approximately the same width as the base support member 12. The clamping block 14 has an aperture disposed centrally therein and extending thereto from top to bottom to correspond with the aperture in the base support 12.

35 The engine block 11 has a threaded aperture 27 which receives a threaded bolt 17 to secure the base support 12, U-shaped rocker fulcrum 13, and clamping block 14 to the block of the engine. The flat washer 15, and a lock washer 16 are placed between the head of the bolt 17 and the clamp block 14. The flat washer 15 protects the clamp block 14, and the lock washer 16 forms the usual function of locking the bolt 17 in position with respect to the engine block 11.

40 The rocker arms are designated generally as 18 and 18a. The rocker arms 18 and 18a are identical in structure and appear on either side of the base support as best shown in Figs. 2 and 3.

45 Since the rocker arms 18 and 18a are identical in structure, only the rocker arm 18 will be described in detail.

50 Rocker arm 18 can be stamped or pressed from steel making it very economical to manufacture. It is generally of a U-shaped channel design with a push rod receiving end 28, and a valve stem receiving end 29 extending from the saddle 30 at the central portion thereof. The end 28 has a cupped seat 24 formed therein to receive and seat the end of a push rod 22. The end 29 has an arcuate bearing surface designed and adapted to abut and slide over the end of a valve stem 23.

55 The U-shaped portion of the rocker arm 18 has a saddle or bearing surface 30 which coacts with the outer surface of the U-shaped rocker fulcrum. The bearing surface 30 is dimensioned so as to form a bearing fit with the outside surface of the U-shaped rocker fulcrum so that the bearing surface 30, when in the position as shown in Fig. 1, fits snugly against and rocks on the outside surface of the U-shaped rocker fulcrum, and the U-shaped rocker fulcrum acts as a bearing therefor.

60 As previously described, the U-shaped rocker fulcrum extends on either side of the base support. Each extended portion of the fulcrum acts as a bearing surface for the rocker arm 18 and rocker arm 18a respectively.

The rocker arms 18 and 18a are held in bearing engagement with either end of the rocker fulcrum 13 by means of a spring designated generally as 21. The spring 21 has limbs or clips 31 and 31a which are bent in an arcuate manner inwardly toward the body of the spring 21. The spring 21 is positioned between the engine block 11 and the bottom of the base support 12. It has an aperture located in the center thereof which corresponds with the aperture in the base support 12, and receives the bolt 17 therethrough. Therefore, the spring 21 is secured in position by being sandwiched between the engine block 11 and the base support 12. The spring limbs or clips 31 and 31a engage the underside of the channel shaped rocker arms 18 and 18a, and assures that the bearing surface 30 and 30a thereof maintain constant engagement with the bearing surface 41 of the rocker fulcrum.

Although spring 21 is a preferred form of the invention, it is to be understood that other spring designs may give comparable results within the broader aspect of the invention.

The cupped seat 24 of the rocker arm 18 has an oil inlet hole 25 in the side thereof. The push rod 22 is hollow and forms a passage for oil from a hydraulic tappet (not shown). The rocker arm 18 has an oil groove 20 positioned transversely thereof in the bearing surface 30. The bearing surface 30 of the U-shaped rocker fulcrum may have the bottom thereof flattened as shown at 19. Both the oil groove 20 and the flattened surface 19 may be used to facilitate lubrication; however, usually only one or the other is necessary. The oil, as it is forced from the hole 25, is gravity fed to lubricate the bearing surface 30 of the rocker arm and the bearing surface 30 of the U-shaped rocker support. The rocker arm 18a has a comparable housing 24a, oil hole 25a, and transverse oil groove 20a.

Having described the structure of the double rocker arm assembly, the operation thereof will now be described.

Operation

The double rocker arm assembly is secured to the engine block 11 by inserting bolt 17 through apertures in the lock washer 16, the flat washer 15, the clamping block 14, the U-shaped rocker fulcrum 13, the base support 12, and the spring member 21, and threading the bolt 17 in the threaded aperture 27 of the engine block. The U-shaped rocker fulcrum assumes the position shown in Fig. 1 and is aligned over the spring clip arms 31 and 31a. Before the bolt 17 is tightened it is an easy matter to slip the rocker arms 18 and 18a under the respective spring arms 31 and 31a and the bearing surfaces 30 and 30a of the rocker arms fit snugly against the bearing surfaces 41 of the U-shaped rocker fulcrum. The bolt 17 can now be tightened to its secured position. The rocker arms 18 and 18a are now in position to receive the hollow push rods 22 and 22a in the respective seats 24 and 24a. The ends 29 and 29a of the respective rocker arms engage the valve stems 23 and 23a.

A double rocker arm assembly is now in operative position. The push rods 22 and 22a are reciprocated in a vertical direction by mechanism of the engine (not shown). The rocker arms 18 and 18a are then caused to rock or oscillate about the U-shaped rocker fulcrum 13. This rocking motion is transferred to the valve stems 23 and 23a and causes them to reciprocate vertically and thereby open and close the valves.

It is apparent that the rocker arm 18 is suspended with respect to the rocker arm fulcrum, rather than being secured thereto or being threaded on a rocker arm shaft. The three points of suspension are at the push rod, spring, and valve stem. The major points of suspension are at the push rod and the valve stem, and the spring arm is present to merely hold the rocker arms in place and assure that the bearing surface 30 of the rocker arm

18 rides against the bearing surface 31 of the rocker support.

It can be seen that a very effective rocker arm has been disclosed which has no apertures at the vital bearing area. Therefore, this rocker arm is much stronger than rocker arms being presently used. The rocker arm 18 has the further advantage of being easy to manufacture. It is a simple matter to stamp or press the rocker arm 18 since there are no apertures to design for.

10 It should be readily apparent that the double rocker arm assembly as disclosed greatly reduces the harmonic vibrations present over many of the rocker arm assemblies now in use. Having only two rocker arms operating from a rocker support rather than, for example, eight 15 rocker arms operating on a rocker arm shaft, obviously will reduce the vibration factor.

Another advantage of this double rocker arms assembly over rocker arms presently in use is that only one fastener 17 is necessary to secure two rocker arms in 20 position with respect to the engine. To secure many of the rocker arms now in use to an engine block, it is necessary to have a fastener such as 17 to secure each and every rocker arm.

Although, the double rocker arm assembly as shown is 25 a preferred embodiment of the invention, it is to be understood that within the broader aspect of this invention one rocker arm rather than two could be suspended from the rocker support similar to the member 13, or the member 13 could be extended and two or more rocker arms 30 suspended from either side of the base support 12.

While a preferred embodiment of this invention has been described, it will be understood that other modifications and improvements may be made thereto. Such 35 of these modifications and improvements as incorporate the principles of this invention are to be considered as included in the hereinafter appended claims unless these claims by their language expressly state otherwise.

I claim:

1. A rocker arm assembly comprising; a support means, 40 fulcrum means, means for clamping said fulcrum means to said support means, said fulcrum means having an arcuate bearing surface, rocker arm means, said rocker arm means having an arcuate bearing surface engaging said fulcrum bearing surface, and means cooperating with said rocker arm means whereby said rocker arm is suspended from said fulcrum means.

2. A rocker arm assembly comprising; a support means, fulcrum means, means for clamping said fulcrum means to said support means, said fulcrum means having an arcuate bearing surface, rocker arm means, said rocker 50 arm means having an arcuate bearing surface engaging said fulcrum bearing surface, and means including biasing means whereby said rocker arm is suspended from said fulcrum means.

3. A rocker arm assembly comprising, a support means adapted to be secured to an engine block, said support means having a saddle formed therein; fulcrum means shaped to seat in said support means saddle, said fulcrum means extending beyond either side of said support means, rocker arm means including a rocker arm engaging each extension of said fulcrum means; means including biasing means whereby said rocker arm is suspended from said fulcrum means, a clamping block engaging said fulcrum means and a fastener adapted to secure said support means, said fulcrum means, said clamping block and said biasing means rigidly to said engine block as a single unit.

4. A rocker arm comprising; a generally U-shaped member, said U-shaped member having flanges extending from either side thereof adapted to engage a push rod and a valve stem respectively, the U-shaped portion of said member having a bearing surface adapted to bear against a support means for purposes of suspending it with respect to an engine, said bearing surface being 75 void of apertures.

5. A rocker arm comprising; a rocker arm means, said rocker arm means having flanges extending from either side thereof adapted to engage a push rod and a valve stem respectively, said rocker arm means having an arcuate bearing surface adapted to bear against a support means for purposes of suspending it with respect to an engine, said bearing surface being void of apertures.

6. A rocker arm assembly comprising; a support means adapted to be secured to an engine block, said support means having a saddle formed therein; fulcrum means shaped to seat in said support means saddle, said fulcrum means extending beyond either side of said support means, a clamping block and fastener means adapted to secure said support means and said fulcrum means rigidly to said block; rocker arm means including a rocker arm engaging each extension of said fulcrum means; biasing means, said biasing means having limbs engaging each rocker arm and forcing them into bearing engagement with said fulcrum means extensions.

7. A rocker arm assembly comprising; a support means adapted to be secured to an engine block, said support means having an arcuate saddle formed therein; fulcrum means shaped to seat in said support means saddle, said fulcrum means extending beyond either side of said support means and having arcuate bearing surfaces formed thereon, a clamping block and fastener means adapted to secure said support means and said fulcrum means rigidly to said block; rocker arm means including a rocker arm engaging each extension of said fulcrum means; each rocker arm having an arcuate bearing surface and a pair of flanges extending from either end thereof, said rocker arms adapted to engage a pair of push rods and valve stems respectively; biasing means engaging said each rocker arm and forcing their bearing surfaces into bearing engagement with said fulcrum means extensions, said flanges and bearing surfaces providing a three point suspension for said rocker arms.

8. A rocker arm assembly comprising; a support means, fulcrum means, means for clamping said fulcrum means to said support means, said fulcrum means having a bear-

ing surface, rocker arm means, said rocker arm means having a bearing surface engaging said fulcrum bearing surface, said rocker arm means having a pair of flanges one of which has a housing adapted to engage a push rod, said housing having an aperture therein adapted to receive oil from said push rod to lubricate said bearing surfaces.

9. A rocker arm assembly as in claim 8 wherein said rocker arm bearing surface has an oil groove therein to house lubricant.

10. A rocker arm assembly comprising: a support means adapted to be secured to an engine block in a position extending upwardly therefrom; a fulcrum secured to the top of said support means and having an extension extending from at least one side thereof in spaced relation above said engine block; a rocker arm engaging the undersurface of said extension; and biasing means at said support and having a limb extending upwardly and engaging said rocker arm forcing it upwardly into bearing engagement with said fulcrum.

11. A rocker arm assembly comprising: a support means adapted to be secured to an engine block in a position extending upwardly therefrom; a fulcrum secured to the top of said support means and having an extension extending from at least one side thereof in spaced relation above said engine block; a rocker arm engaging the undersurface of said extension; and biasing means at said support and having a limb biased upwardly and inwardly toward said support and engaging said rocker arm to force it upwardly into bearing engagement with said fulcrum and prevent it from sliding off the end of said fulcrum.
